Dec 1740

David L. Bartlett, of Baltimore Md.
ass to himself
J. H. Hayward and H. W. Robbins.
Letters Patent No 1740, dated March 24, 1863.

This schedule referred to in these Letters Patent and making part of the same

To all whom it may concern:

I do know that I, David L. Bartlett, of Baltimore City, and State of Maryland, have invented or produced a new and original design for a Stove; and I do hereby declare that the following is a full and exact description of the same, reference being had to the accompanying drawings, making a part of this specification, in which

Figure 1. is a perspective view showing the front and one side of the stove.

Figure 2. shows the design on the side plate and side doors of the stove.

Figure 3. shows the design on the back plate of the stove, and

Figure 4. shows the design on the front doors and door plate.

To enable others to fully understand my design, I will proceed to describe it with reference to the drawings.

The side plate, Figure 2. is surrounded at its outer edge by a bead or moulding a in alto-relief and above the large door, on this plate, is an ornamental festoon b in alto-relief containing the words "Hayward, Bartlett & Co." The large door of this stove plate is surrounded by a cyma-recta moulding, c, and in the middle of this door is a circular rossette d having a button centre. This rossette d is surrounded by the radiating ornament e the edges of which are carried out nearly to the moulding c, as shown in the drawings Fig. 2.

The two smaller doors f and g, fig 2 have a similar moulding to that represented on the edge of the large door and the rossettes f, g in the centres of these doors are like those represented with the ornamentation on the large door, except that the rossette f on the door f is elliptical while the rossette on the large door and that on the small door g is circular. The borders on the small doors f and g are formed with i, but along the edge

of the moulding *i. i.* and each line of this bordering is terminated by a flower "bud" *j. j.* which gives a finish to the corners.

The rosettes and the ground of the ornamentations on the small doors *f. g.* project outwards, or are convex, giving a very bold and beautiful relief adding greatly to the appearance of these doors.

The back plate, figure 3, is quadrilateral and it is surrounded by a moulding *k.* The ground of the three ornamental figures *A, B* and *C*, on this plate is plain and the three figures have a similar ornamentation to the figure shown on the large door on the side plate Fig. 2, except that these figures *A, B, C.* are oblong and the rosettes elliptical. The middle figure, *B.* is the largest, and the smaller figures *A, C.* symmetrize with the largest one.

The front plate Figure 4, has a border which consists of two side columns *l. l.* and a bottom head *m.* extending across the plate from the basis of the two columns. The doors *D. E.* are quadrangular, oblong, and are ornamented with figures similar to the figures on the small oblong door seen in figure 2. The intermediate space between the doors *D. E.* and the columns *l. l.* is ornamented by a plain ogee moulding *n.* which partly surrounds the doors and also a similar moulding *p.* which completely surrounds the register slide *r.* At each end of this register slide is a plain panel *s.* having a knot *s.* projecting from it which gives the panels the appearance of drawers. The intermediate space between the two panels *s. s.* is filled up with square recesses *t. t. t.* surrounded by small mouldings or beads *v. v.*

I do not include as essential the ornaments about the register of the stove, although I have described the same.

What I claim and desire to secure by Letters Patent is,

The ornamentations of the panels of the several plates, as a new design for a Cook Stove, as described and represented.
